Primary Examiner — Robert M. Spear*Assistant Examiner* — Kendra Leslie Hamilton(74) *Attorney, Agent, or Firm* — Carr & Ferrell LLP(57) **CLAIM**

The ornamental design for a dog collar, as shown and described.

DESCRIPTION

FIG. 1 is a top front right perspective view of a dog collar showing my new design in condition of use.

FIG. 2 is a top right front perspective view of the dog collar of FIG. 1.

FIG. 3 is a top left rear perspective view thereof.

FIG. 4 is a top right rear perspective view thereof.

FIG. 5 is a bottom left front perspective view thereof.

FIG. 6 is a bottom left rear perspective view thereof.

FIG. 7 is a rear elevational view thereof.

FIG. 8 is a left elevational view thereof.

FIG. 9 is a top plan view thereof.

FIG. 10 is a right elevational view thereof; and,

FIG. 11 is a front elevational view thereof.

The broken lines are directed to environment. None of the broken lines form a part of the claimed design.

1 Claim, 5 Drawing Sheets(56)
